DRILL STEEL RETAINER

John C. Curtis and Albert Feucht, Garfield Heights, Ohio, assignors to The Cleveland Rock Drill Company, Cleveland, Ohio, a corporation of Ohio

Application August 16, 1935, Serial No. 36,540

6 Claims. (Cl. 279—19.1)

This invention relates broadly to rock drills of the percussive type, but more particularly to improvements in drill steel retainer.

One object of this invention is to produce a releasable drill steel or tool retainer which is simple in design, economic in manufacture, and susceptible of ready manipulation.

Another object of this invention is to provide a drill steel retainer with cushioning means for absorbing the blows of the drill steel against the retainer.

These objects are accomplished by a construction free of complication, and by an arrangement of parts resulting in a compact unit which is strong, durable, and efficient.

In the drawings which illustrate a preferred embodiment of the invention:

Fig. 1 is a side elevational view of the front portion of a rock drill having the invention applied thereto.

Fig. 2 is an end view of the retainer positioned as shown in Fig. 1.

Fig. 3 is a sectional view of a portion of the retainer, the section being taken through a plane indicated by line 3—3 in Fig. 1.

Fig. 4 is a sectional view taken through a plane indicated by line 4—4 in Fig. 3.

Fig. 5 is a side elevational view of a portion of a rock drill having a modified form of the invention applied thereto.

Fig. 6 is a sectional view taken through a plane indicated by line 6—6 in Fig. 5.

Fig. 7 is also a sectional view taken through a plane indicated by line 7—7 in Fig. 6.

Fig. 8 is also a side elevational view illustrating another modification of the invention.

Fig. 9 is a sectional view taken through a plane indicated by line 9—9 in Fig. 8, and

Fig. 10 is also a sectional view taken through a plane indicated by line 10—10 in Fig. 9.

Referring to the drawings in which like symbols designate corresponding parts throughout the several views, there is shown a front housing 15, which is secured to the rock drill by bolts 16 and co-operating nuts 17. The housing 15 is of the type adapted to slidably receive the shanks of a drill steel 18 having a collar 19 formed integral therewith, and engageable with the front end of the housing 15, for limiting the penetration of the drill steel shank into the housing.

Toward its forward extremity, the housing 15 is provided with a transversely disposed boss 20 formed on one side thereof. The ends of the boss are spot faced to form circular lands 21, from which extend upwardly bosses or ribs 22 also

formed integrally with the housing 15. The boss 20 is formed with a relatively large cylindrical aperture 23, within which is located a sleeve 24 formed of resilient material such as rubber. In the sleeve 24 is inserted a shaft 25, which has its end portions protruding from the ends of the boss 20. These end portions are provided with relatively large grooves 26 having side walls 27 and 28 extending part way around the shaft. The bottom of the grooves is turned eccentrically with 10 the shaft, but of a radius equal to that of the latter.

Partly surrounding the drill steel 18 below the collar 19, there is a yoke or retainer 29 capable of engagement with the collar 19 to prevent the 15 accidental removal of the drill steel shank from the front housing 15. The yoke 29 is provided with parallel side arms 30 extending upwardly therefrom. Each of the side arms 30 is terminated by an enlargement 31 having an aperture 20 32 transversally therethrough, which is adapted to receive the corresponding grooved end of the shaft 25. The width of these enlargements is somewhat less than that of the grooves 26, permitting thereby the former to drop within the 25 latter with the upper wall portion of the apertures 32 in pivotal engagement with the arcuated bottom wall of the grooves 26, and the side walls 27 and 28 of each groove capable of engagement with the corresponding side wall of the enlargements 31.

Formed within each of the ribs 22, there is a flat bottom bore 39 having a plunger 33 slidably therein. This plunger is constantly urged in engagement with the peripheral wall of the enlargement 31 due to the effort of a compression spring 34, which is interposed between the plunger 33 and the bottom 45 of the bore 39. The peripheral wall of each enlargement 31 is formed with two flats or stops 35 and 36, with which the plunger 40 33 is engageable for maintaining the yoke in open or closed position relative to the drill steel 18.

In the modified form of the invention shown in Figs. 5, 6, and 7, the aperture 37 formed through the front housing boss 20 is of an oblong shape. 45 Located between the shaft 25 and the bottom of the aperture 37, there is a member 38 also formed of resilient material such as rubber. This member is of a crescent shape as shown in Fig. 7, and is adapted, like the sleeve 24, to absorb the blows 50 of the drill steel against the retainer.

In the modification illustrated in Figs. 8, 9, and 10, the shaft 40 extending through the resilient sleeve 24 is cylindrical throughout. The end portions of this shaft also protrude from the ends 55

of the boss 20 to pivotally receive the enlargements 41 of the yoke side arms 30. Leading from the inner side wall of each of the enlargements 41, there is an oblong counterbore 42 adapted to 5 pivotally receive the corresponding end portion of the shaft 40, which may be introduced therethrough a cylindrical aperture 43 leading from the bottom of the counterbore 42 to the external side wall of the enlargement 41. The bottom of 10 each counterbore 42 forms a side wall 44 capable of engagement with the corresponding end of the shaft 40 for preventing the accidental removal of the latter. Since the rest of the mechanism of 15 the two modifications illustrated in Figs. 5 to 10 is a replica of that illustrated in Figs. 1 to 4, no further explanation is thought necessary.

In assembling the device, the resilient sleeve 24 is first introduced into the aperture 23 of the boss 20. The yoke is then positioned with the 20 aperture of the enlargements 31 thereof, in alignment with the interior of the sleeve 24 by compressing the springs 34. The shaft 25 is then introduced through the enlargements 31 and sleeve 24, until the upper portion of the former drop in the corresponding grooves 26 of the shaft 25. The side wall 27 of each groove 26 engaging the external side wall of the corresponding enlargement 31, prevents the accidental removal of 25 the shaft 25 as well as the spreading of the 30 parallel arms 30 of the yoke 29.

In operation, the yoke 29 is held in a closed position relative to the passage of the drill steel collar 19, due to the forcible engagement of the spring pressed plungers 33 with the flats 35. 35 The downward pressure exerted by the plungers 33 also maintains the shaft 25 in interlocking engagement with the upper end of the side arms 30 for preventing the accidental removal of the shaft. In the construction shown in Figs. 40. 1 to 7 inclusive, the pressure exerted by the plungers 33 also maintains the shaft 25 in engagement with the enlargements 31 for preventing the spreading of the side arms 30. When it is desired to remove the drill steel from the 45 housing 15, the yoke 29 may be rocked into the position shown in dotted lines in Fig. 1, thus permitting a free removal of the drill steel. The yoke is also maintained in open position due to the engagement of the spring pressed plungers 50 33 with the flats 36.

From the foregoing description, it will be seen that the device is very simple in design and manufacture. The accidental blows delivered to the yoke 29 by the collar of the drill steel, being 55 absorbed by the resilient material interposed between the shaft 25 and housing 15, will reduce wear and prevent possible breakage of the operating parts, thus increasing the life of the device as well as reducing the operating cost 60 thereof.

We claim:

1. A steel retainer for a rock drill comprising in combination with a front housing and a drill steel, a boss on one side of said housing having 65 an aperture therethrough, a yoke for retaining the drill steel in said front housing, side arms extending upwardly from said yoke, a removable shaft extending through said aperture and engaging said side arms to serve as a pivot for the 70 yoke, means integral with said shaft engageable with said side arms for preventing the accidental removal of said shaft from said housing, and means carried by said housing exerting pressure on said side arms for maintaining the

same in interlocking engagement with the means on said shaft.

2. A steel retainer for a rock drill comprising in combination with a front housing and a drill steel, a yoke for retaining the drill steel in said front housing, side arms extending from said yoke, an anchoring device between said arms and housing including a boss on said housing having a removable shaft therein, said shaft engaging said side arms to serve as a pivot for 10 said yoke, said shaft being formed with integral surfaces capable of interlocking engagement with said side arms for preventing the accidental removal of said shaft from said housing, and means operatively associated with said device 15 for maintaining the interlocking engagement aforesaid.

3. A steel retainer for a rock drill comprising in combination with a front housing and a drill steel, a yoke for retaining the drill steel in said front housing, side arms extending from said yoke, a connecting mechanism between said housing and said side arms including a shaft carried by said housing and engaging said side arms to serve as a pivot for said yoke, means 20 integral with said shaft and capable of interlocking engagement with said side arms for preventing the spreading thereof, and means operatively associated with said connecting mechanism for maintaining the interlocking engagement 25 of the means on said shaft with said side arms. 30

4. A steel retainer for a rock drill comprising in combination with a front housing and a drill steel, a boss on one side of said housing having an aperture therethrough, a yoke for retaining the drill steel in said front housing, side arms extending from said yoke to said aperture, a shaft through said aperture, a semi-annular groove formed in each end portion of said shaft 40 adapted to receive the end portion of said side arms for pivotally securing said yoke to said front housing, and means carried by said front housing exerting pressure on the side arms of said yoke for maintaining the same in pivotal 45 engagement with the bottom wall of the grooves of said shaft.

5. A steel retainer for a rock drill comprising in combination with a front housing and a drill steel, a boss on one side of said housing having an aperture therethrough, a yoke for retaining the drill steel in said front housing, side arms extending upwardly from said yoke, a shaft extending through said aperture and having its end portions extending through the upper end 55 of said side arms to serve as a pivot for said yoke, and means on said end portions integral with said shaft operatively engageable with said side arms for detachably locking said shaft against removal from said front housing. 60

6. A steel retainer for a rock drill comprising in combination with a front housing and a drill steel, a shaft carried by said housing on one side thereof, a drill steel retaining yoke having side arms extending upwardly therefrom, an aperture extending through the upper end of each of said side arms, said shaft extending into said apertures to serve as a pivot for said yoke, and means integral with said side arms operatively engageable with the end walls of said shaft for 70 detachably locking said shaft against removal from said front housing.
